AIR CONDITIONING APPARATUS FOR RAILWAY CARS

William B. Whitsitt, Baltimore, Md.

Application April 24, 1936, Serial No. 76,268

12 Claims.

(Cl. 257—3)

This invention relates to an air conditioning apparatus, and particularly to an all-year-round air conditioning apparatus or system for railway passenger cars.

One object of the invention is to provide novel and improved means for supplying properly purified and humidified warm air to the car during the winter season and at such other times as when heating of the car is required for comfort of the passengers.

Another object of the invention is to provide means for supplying properly purified and dehumidified cool air to the car during the summer season or at such other times or under climatic conditions requiring for the comfort of the passengers reduction of the temperature inside the car in comparison with the outside atmosphere.

Still another object of the invention is to provide a novel construction and arrangement of warm and cool air circulating distributing means including air ducts whereby the supply of warm air through the warm air distributing duct or ducts may be arrested when the internal temperature exceeds a predetermined degree, and whereby fresh air, properly tempered if desired, may be supplied through the cool air duct or ducts and the air kept in circulation to prevent it from stratifying until the temperature is reduced to the predetermined degree.

Still another object of the invention is to provide automatic means governed by temperature conditions in the car for regulating the supply of warm air and cool air to the car so as to maintain a substantially constant predetermined warm temperature within the car without the aid or intervention of the services of any of the members of the train crew for such purpose.

Still another object of the invention is to provide a novel construction and arrangement of the warm and cool air distributing ducts whereby a proper and uniform distribution of the air is effected through the aid of natural forces, and whereby either warm or cool air may be furnished without material radiation or other temperature losses.

Still another object of the invention is to provide novel and improved means for heating the air, for humidifying the heated air, and for directly heating the toilet compartments of the car by the same means employed for heating the circulating air in a simple but reliable and effective manner.

Still another object of the invention is to provide means whereby during mild weather conditions, and when the use of the main heating and

cooling devices is not required, fresh outside air, either at outside temperature or mildly heated, may be economically supplied to temper the inside air in order to keep the inside air wholesome and at a comfortable temperature.

Still another object of the invention is to provide an all-year-round air conditioning apparatus of high efficiency which may be installed, operated and maintained in condition for efficient action at a comparatively low cost and in which parts of the warm and cool air supplying equipment coact under the conditions noted to enable the number of working parts to be reduced and the apparatus simplified.

With these and other objects in view, the invention consists of the features of construction, combination and arrangement of parts, hereinafter fully described and claimed, reference being had to the accompanying drawings, in which:—

Fig. 1 is a side elevation of a railway passenger car embodying my invention, portions of the car appearing in vertical section.

Fig. 2 is a top plan view of the car with portions appearing in horizontal section.

Fig. 3 is an enlarged longitudinal section through one end of the car.

Fig. 3a is an enlarged longitudinal section through the opposite end of the car.

Fig. 4 is a section on the line 4—4 of Fig. 3a.

Fig. 5 is a horizontal section through one end of the car.

Fig. 5a is a horizontal section through the opposite end of the car.

Fig. 6 is a diagrammatic view showing the piping of the system.

Fig. 7 is a sectional view showing the steam supply valve and vapor regulator, the valve appearing in open position.

Fig. 8 is a similar view of the steam supply valve showing the same in cut-off position.

Fig. 9 is a diagrammatic view of parts of the apparatus and showing the control circuits.

Fig. 10 is a fragmentary inside elevation of one of the warm air ducts with parts broken away and in section.

Figs. 11, 12 and 13 are sections taken on the lines 11—11, 12—12 and 13—13 of Fig. 10.

Referring now more particularly to the drawings, A designates a railway passenger car of a conventional type having a saloon or passenger compartment B, end vestibules C and C' and spaces D and D' between the vestibules and ends of the compartment, the space D being divided into an air conditioning compartment E and a lavatory or toilet compartment F and the space

D' into an air circulating compartment E' and toilet compartment F', said compartments at each end of the car being arranged on opposite sides of a central passage G forming a passageway 5 between the end vestibule at that end of the car and the center aisle H of the saloon B of the car. The invention is not limited in application, however, to this particular type of passenger car shown for purpose of exemplification, as it may 10 be used with equal efficiency on other types of passenger cars.

The means for supplying cool conditioned air to the car during warm weather periods is conventionally shown herein and may be of direct 15 compressor-condenser-expander type using a non-toxic volatile refrigerant, as disclosed in my prior application Serial No. 598,260, filed March 11, 1932, now Patent No. 2,046,666 issued July 7, 1936 or of any other type, and includes an air 20 duct I extending at or near the ceiling line centrally and longitudinally from end to end of the passenger compartment B, said duct being closed at one end 2 and communicating at its opposite 25 end with an air supply conductor 3 and being provided at intervals throughout its length within the compartment B with grilles or louvered outlets 4 for the discharge of the cool conditioned air into the top of the compartment B. Each 30 passage G is in normally open communication with the compartment B, and the air conditioning compartment E at the end of the car at which the conductor 3 is located is in communication with the adjacent passage G (and therethrough with the compartment B), through an air return or recirculating passage 5 and grille or air 35 inlet 5a. Located within the compartment E at that end of the car at which the conductor 3 is located is a vertically disposed air conditioning unit resting on or supported near the floor of 40 the compartment E comprising a casing 6 containing an air cooling coil 7 into which the refrigerant is expanded, an air inlet chamber 8 beneath this coil, into which chamber air from the compartment E is drawn through a filter 9 which 45 removes foreign impurities from the air, a cooled air discharge chamber 10 above the coil, and an electric motor driven suction and discharge fan 11 in the chamber 10. This fan draws air through the filter inlet 9 and over the coil 7, whereby the 50 air is cooled and dehumidified to the desired degree, and then forces the air from the chamber 10 through the conductor 3 into the duct I for distribution through the outlets 4 into the compartment B. The system for supplying cooled 55 conditioned air further includes one or more air and water cooled condensers 12, a compressor 13, and means of a suitable character for supplying cooling water to the condenser, said parts being operatively connected as shown in my aforesaid 60 application Serial No. 598,260 now Patent No. 2,046,666 issued July 7, 1936 or in any other suitable manner. The position of the air conditioning unit 6 may accord, if desired, with that shown in my Patent No. 1,882,537, issued October 65 11, 1932. One or more axle-driven generators 14, of a type shown in my application Serial No. 584,479, filed January 2, 1932, now Patent No. 2,053,983, issued Sept. 8, 1936 or of an other suitable type, may be provided for furnishing 70 electric current to one or more accumulators or storage batteries 15 and to circuits in which the batteries, compressor and various fans of the system are arranged for driving the compressor and fans. These electrical appliances may also 75 constitute means for supplying current to the light-

ing system and various other electrical appurte- 5 nances of the car. The air cooling and dehumidi- 10 fying system above described is used in the sum- 15 mer months and under climatic conditions re- 20 quiring cooling of the air in the car, the air being 25 recirculated through the recirculating grille and 30 cooled and dehumidified in the cooling compart- 35 ment on each cycle of travel. Ventilators 16, 40 which may be of either automatic or hand oper- 45 ated type, are provided for discharge at proper 50 periods of vitiated air, and a fresh air intake 17, 55 connected with the compartment E, and which 60 may be provided with a suitable damper or shut- 65 ter and with a filter like the filter 9, is provided 70 for the entrance and mixture of outside fresh 75 air with the circulating air to maintain the air 80 in the car in a wholesome condition. At the 85 point of connection of this intake 17 with the 90 compartment E a small steam heater 18 may be 95 provided to heat the incoming fresh air when 100 too cold for mixture at its natural temperature 105 with the recirculating air. The heater 18, of 110 course, is cut out of action during the summer 115 months and at all other times when it is not 120 required or desired to heat the incoming fresh 125 air. The duct I and intake 17 are also employed 130 as elements of the conditioned warm air supply- 135 ing means under certain conditions, as herein- 140 after described.

The means for supplying conditioned warm air 145 to the car during cool or cold weather comprises 150 heater ducts 19 and 20 extending longitudinally 155 of the compartment B in the region of the floor 160 line. Each of these ducts (Figs. 11 to 13) com- 165 prises a casing divided by a partition 21 into an 170 outer air conducting chamber or channel 22 and 175 an inner heating chamber or channel 23. Each 180 of these ducts is closed at one end and has its air 185 channel connected at its opposite end with a 190 vertical duct 24, the ducts 24 leading to the air 195 channels of the respective ducts 19 and 20 being 200 arranged in the compartments E and E' at oppo- 205 site sides of the opposite ends of the car. Each 210 duct 24 connects at its upper end with a cham- 215 ber 25 having an air inlet opening therein com- 220 municating, in case of the duct associated with 225 compartment E with that compartment and in 230 case of the duct associated with compartment E' 235 with the adjacent passageway G, and each of 240 these air inlet openings is guarded by a filter 245 to strain foreign impurities from the air entering 250 the chamber 25. Motor driven fans 27 and 27' 255 are disposed in the chambers 25 of the compart- 260 ments E and E' and in operation each fan draws 265 air through the associated filter inlet 26 and 270 forces the air into the intake end of the air 275 conducting chamber 22 of the associated longi- 280 tudinal duct.

In the vertical wall portion of the partition 21 285 of each duct 19 and 20 is a longitudinal air feed 290 slot 28 extending the full length of the duct and 295 through which the air feeds from the chamber 22 300 to the chamber 23 which is provided in the 305 vertical wall of the duct separating it from the 310 compartment B with outlet grilles 29 arranged at 315 regular intervals apart in the length of the duct. 320 In the chamber 23 of each heater duct is a steam 325 heating unit preferably formed of a looped pipe 330 composed of an upper feed pipe or branch 30 335 and a lower heating pipe or branch 31, said unit 340 extending longitudinally within the chamber 23 345 and being secured therein at intervals to brackets 32 by anti-rattler clamps 33. The upper pipe 350 or branch 30 of each heating unit is preferably 355 used as a simple conductor for feed of steam 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

from the main steam supply pipe 34 on the car to the lower pipe or branch 31 which is employed as the air heating element and provided for that purpose with fins 35 to increase its heating area. 5 The air passing from the chamber 22 to the chamber of each heater duct is thus heated to the desired degree by the heater unit and is discharged in a properly heated state to the compartment B. The size of the slot 28 is such that 10 it acts as a regulator to supply to the chamber 23 air in such volume as to be heated to the desired degree on its travel to the discharge grilles, and the slots of the respective heater ducts regulate the volume of the air supplied to the compartment B in amount to keep the air wholesome 15 and the compartment at a comfortable temperature. Preferably the ends of each heating pipe loop extend into the compartments E and F or E' and F' at its side of the car and both pipe 20 branches at such ends of the loop are provided with fins 36 giving sufficient radiating surface to heat such compartments in cold weather to a comfortable degree, whereby a simple and economical way of heating the said compartments 25 is furnished.

In order to humidify the heated air in winter time there is disposed in one or both of the heating ducts a humidifier 37 shown in detail in Figs. 10 and 11. This humidifier is controlled by a 30 commercial humidostat 38 located on one of the walls of the car which can be set at a desired relative humidity, generally about 35%. The humidifier shown is of the steam actuated type, although any other suitable type of humidifier 35 can be used. This humidifier comprises a brass or copper pipe 39 in the bottom of which is cut a slot 40 in which is inserted and properly secured the upper edge of a depending sheet or apron 41 of small gauge mesh screen brass or 40 other non-rusting wire, said pipe and screen being arranged in the chamber or channel of the duct in the path of the heated air flowing to the outlet grilles. When the humidostat opens to 45 raise the humidity in the car steam from the main supply pipe 34 is blown through the slot in the pipe 39 where it immediately condenses and the water of condensation trickles down over the fine mesh screen sheet 41, the air flowing through the meshes of the screen picking up the 50 moisture and carrying it through the grilles and distributing the moisture throughout the body of air in the compartment B of the car, thereby increasing the relative humidity. When the humidity in the compartment B exceeds the predetermined 55 degree the humidostat closes to cut off the supply of steam to the pipe 39 until the humidity again falls below the predetermined rate.

The steam and current supplying systems of the apparatus are shown in Figs. 5, 6, 7 and 9. 60 The steam supply system includes, besides the pipes 30, 31, 34 and 39, a branch pipe 42 leading from the pipe 34 to the heater 18, in which branch pipe is a controlling and cut off valve 43, a branch pipe 44 leading to the pipe 39 and in which a cut off valve 45 for cutting the humidostat out of action for any length of time, an electromagnetically operated valve 46 controlled by the humidostat 38, electromagnetically 65 operated valves 47, a thermostatic switch 48 controlling the action of fans 27 and 27' and governing the valves 47 for cutting on or off the supply of steam to the air heating pipes in the ducts 19 and 20 for regulation of the temperature in the compartment B when the air heating system 70 is in use, and a regulator 49 associated with each

valve 47 for controlling the supply of steam thereto. As shown, each valve 47 comprises a casing provided with chambers 50, 51, 52, 53, the chamber 50 being of circular form and having arranged therein an oscillatory rotary and partitioned valve member 54 controlling communication between said chambers. The pipe 30 is connected by a branch 55 intermediately of its length with the valve chamber 50, while the pipe 31 is divided into two branches joined by a loop 56 connected by a branch 57 with the chamber 51. The valve member 54 is movable between the on position shown in Fig. 7 and the off position shown in Fig. 8. The regulator 49 comprises a casing having an intake port 58 connected with the steam supply pipe 34, a feed port 59 connected by a pipe 60 with the valve chamber 52, and a return port 61 connected by a pipe 62 with the valve chamber 53. A valve 63 controls the feed of steam from port 58 to port 59 and is coupled 20 by a connection 65 to a control diaphragm 66. When the valve member 54 is open, as shown in Fig. 7, communication is established between pipe 31 and chambers 51 and 53 and port 61, the diaphragm 66 operating to hold valve 63 open 25 so that steam from the line 34 passes through port 58, pipe 60, chamber 52, valve 54 and branch 55 to pipe 30 for circulation of steam through the pipes 30 and 31 in amount and at a pressure governed by the position of valve 63 controlled by 30 the diaphragm 66. When the valve 54 is closed, as shown in Fig. 8, communication is closed between the connection 57 and the chambers 52 and 53 leading from and to the regulator and communication is established between chambers 35 52 and 53 and the regulator and between connection 57 and drain chamber 51 so that valve 63 is closed under action of diaphragm 66 and any water of condensation entering chamber 51 from the heating pipes may discharge. In 40 this closed position of the electromagnetically operated valve occurring during the operation of the heating system in cold weather, at a time when the compartment B is heated above a predetermined temperature, the supply of steam to the 45 heating pipes is cut off to prevent further overheating of the car on the building up of a pressure more than slightly above atmospheric pressure. The regulator is so constructed that in a closed position of the valve a slight occasional 50 movement of the diaphragm 66 occurs to open the valve 63 to permit a small quantity of steam to pass to the electromagnetically operated valve, sufficient to prevent freezing thereof in cold weather if arranged in an exposed position. 55

The action of the valve 46 is controlled, as above described, by means of the humidostat 38 arranged with the valve in a branch of one of two electrical control circuits including the fans 11, 27 and 27', the arrangement being such that 60 the fan 11 may be operated with the air cooling means for summer cooling but may be operated without the air cooling means when the air heating and circulating fans are cut out of action for any period of time as when the compartment B 65 is overheated and it is desirable to supply fresh cool air to cool off the compartment to the normal temperature desired and to freshen the air. Automatic electrical means are, therefore, provided, set into action at proper temperatures by 70 thermostatic switch 48 to automatically and alternately throw the fans 11 and 27-27' and valves 47 into and out of action at predetermined temperatures. The means provided for this purpose comprises a circuit 67 in which the fan 11 75

is included and a circuit 68 having control branches 69 and 70, branches 71 controlling the valves 47 and a branch 72 controlling the valve 46. A switch 73 arranged between magnets 69' and 70' in the branches 69 and 70 is movable in one direction to engage contacts 74 to close the circuit 67 and in the opposite direction to engage contacts 75 to close circuits to fans 27 and 27'. Closing of the circuit 67 by switch 73 will set the 10 fan 11 into operation to supply cool air through the duct 1 into compartment B, while movement of switch 73 into engagement with contacts 75 will put heater fans 27 and 27' in operation. The 15 thermostatic switch 48 is controlled in action by the temperature in compartment B and includes a switch member 76 which governs the action of switch 73 and the valve 47. This thermostatic switch member 76 is movable to engage contacts 77 to close circuit branch 69 and energize the 20 magnet to move switch 73 into engagement with contacts 74, and said switch 76 is movable to engage contacts 78 to close branch 70 and energize magnet 70' to move switch 73 out of engagement with contacts 74 and into engagement with contacts 75 and to close branches 71 and 72 for action. The thermostat is set to engage switch member 76 with contacts 78 at all times when the temperature in compartment B is at or below a predetermined degree, say from 68° to 70° 25 F., whereby the steam supply valves 47 are held open to supply steam to the heating pipes and the fans 27 and 27' are driven to force air to and through the ducts 19. If, however, the temperature should rise above this degree the thermostat 30 will move switch member 76 out of engagement with contacts 78 and into engagement with contacts 77, thus closing the steam supply valves 47 and cutting off the supply of steam to the heating pipes and stopping the fans 27 and 27' and de- 35 energizing the magnet 70' and energizing the magnet 69' to throw switch 73 into engagement with contacts 74 to close circuit 67 and start fan 11 into action to supply cool fresh air through the duct 1 into the compartment B. When the 40 temperature in the passenger compartment is reduced to the proper degree the switches are operated to throw the steam supplying means and the fans 27 and 27' again into action, and to 45 throw the fan 11 out of action, as will be readily understood.

From the foregoing description, it will be seen that my invention provides an all-year-round system for cooling and otherwise conditioning and circulating the air during warm weather 50 periods, so as to keep the temperature in the passenger compartment comfortable during such weather periods, and for warming and otherwise conditioning and circulating the air during cool or cold weather periods so as to maintain the temperature of the air in the passenger compartments at a comfortable degree during such weather periods. The air supplied to the passenger compartment during warm weather periods is free from impurities and properly de- 55 humidified, while the air supplied during cold weather periods is likewise free from impurities and humidified, so that at all times of the year a comfortable temperature and wholesome condition of the air may be maintained in the passenger compartment. During warm weather periods it will, of course, be understood that the cooling unit and associated parts of the cooling system will be employed in conjunction with the fan 11 to supply cool air at the proper temperature to 60 the passenger compartment, while during cold

weather seasons and the use of the air heating and distributing means, the air cooling mechanism is cut out of action with the exception of the duct 1 and fan 11 which may be employed in the manner described in connection with the duct 1 for keeping the air in circulation and preventing it from stratifying. In the operation of either the cool or warm air conditioning and distributing means, recirculation of the air is provided for by the provision of the recirculating grille, the filter opening 36 and the openings connecting compartment E with the passenger space and the recirculated air may be combined in the operation of either the cool air or warm air system by fresh outside air drawn in through the conductor 17 by either the fan 11 or the fan 27, this fresh outside air being forced with the recirculated air into the passenger compartment through the distributing ducts. If at any time the amount of fresh air drawn in with the recirculated air is not regarded as sufficient to maintain the purity of the air stream, vitiated air at the top of the passenger compartment may be discharged by opening the air ventilators. In general, however, this system of summer and winter air conditioning equipment ensures both circulation of the air through either the top center distributing duct or the two bottom longitudinal heating ducts without the use or necessity of operating any dampers or damper motors. Great 30 efficiency of operation of the system is secured by the use of natural forces in effecting the circulation of warm and cool air, the cool air supplied through the overhead center duct ascending by gravity and taking the place of rising warmer 35 air, while the warm air supplied through the heating ducts by reason of its lightness rises and quickly heats the passenger carrying space, all without the use of dampers or other means for controlling the flow and properly distributing 40 the air. It will be understood that a switch 79 may be provided for closing the circuit 67 independently of the switch 73 so that the fan 11 may be used alone or with the cooling means for distributing the air in warm or mild weather, and 45 that a switch 80 may be provided to cut out the circuit 68 when the use of the air heating and circuiting devices is not required.

It will be understood that there are seasonal periods of mild weather or climatic conditions 50 during which the use of the air cooling and heating units is not necessary as they are in hot weather or cold weather to keep the air in the passenger compartment at a comfortable temperature. During such mild weather periods the air in the passenger compartment may become 55 too close and slightly too warm or slightly too cool. It is desirable under these conditions to freshen and temper the air without, for economic and other obvious reasons, putting the air cooling or air heating units into use. The ducts 1 and 17, fan 11 and heater 18 provide a means whereby outside air, either unheated or heated by the heater 18, may be circulated to keep the air in compartment in motion and to supply for admixture therewith cool outside air or heated 60 air either to cool down or take the chill off the air in compartment B to a satisfactory degree without the expense or possible discomforts produced by operation of the complete cooling or 65 heating units.

It will be noted that the heated air supplied to the compartment B is heated directly within a distributing duct compartment which is in direct communication through the distributing 70 75

grilles with the compartment B and at the same time insulated from the walls of the car. By this means loss of heat by radiation to the outside of the car body is avoided. Hence economy in the use of the heating agent is secured and it is not necessary to heat the air to an excessive degree in order to allow for radiation losses. The air introduced, in fact, is substantially of the same temperature as that in the car, assuring 10 that the air in the car is at the intended predetermined temperature, and is therefore in a fresh and more wholesome condition than if more highly heated, requires less humidification, and is free from odors and objections incident to 15 the use of highly heated air.

While in the drawings I have shown a preferred exemplification of the invention, it is to be understood that the invention is not limited thereto, as changes in the arrangement, construction, form and proportions of the parts may be made, within the scope of the appended claims, without departing from the spirit or sacrificing any of the advantages of the invention.

What I claim is:—

25 1. In an air conditioning apparatus for passenger vehicles, a duct extending longitudinally of the bottom portion of the passenger space of the vehicle for supplying heated air thereto, a duct extending longitudinally of the upper portion 30 of the passenger space of the vehicle for supplying cool air thereto, fans for passing warm and cool air through the respective ducts, means governed by the degree of humidity of the air in the vehicle for humidifying the air heated in 35 the heated air supplying duct, and temperature controlled means for automatically and alternately cutting in and cutting out the warm and cool air fans for maintaining a substantially uniform degree of temperature in the passenger 40 space.

2. In an air conditioning apparatus for passenger vehicles, means including a distributing duct and a circulating fan for supplying and distributing heated air to the passenger space 45 of the vehicle, means including a distributing duct and a circulating fan for supplying and distributing relatively cool air to the passenger space of the vehicle, means controlled by the humidity of the air in the passenger space for humidifying the heated air, and means governed by the temperature of the air in the passenger space for throwing said heated air and cool air 50 circulating fans into and out of action to maintain a predetermined degree of temperature in 55 said passenger space.

3. In an air conditioning apparatus for passenger vehicles, a duct extending longitudinally of the passenger space of the vehicle for supplying heated air thereto, means for heating the air passing through the duct, means for forcing air through the duct, means including a forcing device for supplying outside air to the passenger space, means governed by the degree of humidity of the air in the vehicle for humidifying the air heated in the duct, and temperature controlled 60 means for automatically cutting the heat supplying means and associated forcing device into and out of action and throwing said fresh air forcing device into action when the heat supplying means and associated forcing device are cut 65 out of action.

4. In an air conditioning apparatus for passenger vehicles, warm air supplying ducts extending longitudinally at opposite sides of the bottom 70 of the passenger space of the vehicle, a cool air

supplying duct extending centrally and longitudinally at the top of the passenger space of the vehicle, air heating means disposed in at least one of said warm air supplying ducts, means in said duct for humidifying the air, fans arranged 5 at the opposite ends of the vehicle for forcing air in opposite directions through the respective warm air supplying ducts, a fan located at one end of the vehicle for forcing air through the cool air supplying duct, and temperature controlled means for automatically cutting the heating means and the fans associated with the warm air supplying ducts out of action when a predetermined temperature in the passenger space is exceeded and simultaneously throwing the cool 10 air supplying fan into action, said means being operative to reverse such actions when the temperature falls to the predetermined degree.

5. In an air conditioning apparatus for passenger vehicles, a duct extending longitudinally 20 of the bottom portion of the passenger space of the vehicle for supplying heated air thereto, means for heating the air passing therethrough, means for humidifying the air passing therethrough, a duct extending longitudinally of 25 the upper portion of the passenger space of the vehicle for supplying cool air thereto, air cooling means, means for forcing air through the warm air duct, means for forcing air cooled by the cooling means or for supplying outside atmos- 30pheric air through the cool air duct, and temperature controlled means for automatically and alternately cutting in and cutting out the heating means and warm and cool air fans for maintaining a substantially uniform degree of temperature in the passenger space. 35

6. In an air conditioning apparatus for passenger vehicles, a duct extending longitudinally of the bottom portion of the passenger space of the vehicle adjacent one of the side walls thereof 40 for supplying heated air thereto, said duct having a partition dividing it into an air admission compartment lying next to said side wall and a heating compartment facing the passenger space and provided with air outlets communicating 45 therewith and said partition being provided with an air passage connecting said chambers, means in the air heating chamber for heating the air passing therethrough, a fan for forcing air through said duct, a duct extending longitudinally of the upper portion of the passenger space of the vehicle for supplying cool air thereto, means for cooling air to be supplied to the cool air duct, a fan for forcing air through the cool air duct, and temperature controlled means 50 for automatically cutting off the supply of heating medium to the heating duct and throwing the fan associated therewith out of action when a predetermined temperature is exceeded and simultaneously throwing the cool air supplying fan 55 into action, said means being operative to reverse such actions when the temperature falls to the predetermined degree.

7. In an air conditioning apparatus for passenger vehicles, warm air supplying ducts extending longitudinally at opposite sides of the bottom 60 of the passenger space of the vehicle, each of said ducts having a partition dividing it into an air admission compartment lying next to said side wall and a heating compartment facing the 65 passenger space and provided with air outlets communicating therewith and said partition being provided with an air passage connecting said chambers, a cool air supplying duct extending centrally and longitudinally at the top of the pas- 70

- senger space of the vehicle, air heating means disposed in the heating chamber of at least one of said warm air supplying ducts, fans for forcing air through the respective warm air supplying ducts, air cooling means, a fan for forcing air cooled by said cooling means through the cool air supplying duct, and temperature controlled means for automatically cutting the heating means and the fans associated with the warm air supplying ducts out of action when a predetermined temperature in the passenger space is exceeded and simultaneously throwing the cool air supplying fan into action, said means being operative to reverse such actions when the temperature falls 15 to the predetermined degree.
8. In an air conditioning apparatus for passenger vehicles, a duct extending longitudinally of the bottom portion of the passenger space of the vehicle for supplying heated air thereto, said 20 duct having an air admission chamber and an air discharge chamber separated by a partition having a longitudinal slot therein for passage of air from the one chamber to the other, means for heating the air passing through said duct, means 25 for humidifying the air passing therethrough, a duct extending longitudinally of the upper portion of the passenger space of the vehicle for supplying cool air thereto, air cooling means, means for forcing air through said warm air duct, means 30 for forcing air cooled by the cooling means or for supplying outside atmospheric air through the cool air duct, and temperature controlled means for automatically and alternately cutting in and cutting out the heating means and warm and 35 cool air forcing means for maintaining a substantially uniform degree of temperature in the passenger space.
9. In an air conditioning apparatus for passenger vehicles, a duct extending longitudinally 40 of the bottom portion of the passenger space of the vehicle for supplying heated air thereto, said duct having an air admission chamber vertically divided to provide an air admission chamber and an air discharge chamber arranged longitudinally of the space in parallel relation to each other and in communication with each other, means for 45 heating the air passing through said duct, means for humidifying the air passing therethrough, a duct extending longitudinally of the upper portion of the passenger space of the vehicle for supplying cool air thereto, air cooling means, means for forcing air through said warm air duct, means for forcing air cooled by the cooling 50 means or for supplying outside atmospheric air through the cool air duct, and temperature controlled means for automatically and alternately cutting in and cutting out the heating means and warm and cool air forcing means for maintaining a substantially uniform degree of temperature in the passenger space.
10. In an air conditioning apparatus for passenger vehicles, a duct extending longitudinally of the bottom portion of the passenger space of the vehicle for supplying heated air thereto, said 55 duct having an air admission chamber and an air discharge chamber separated by a partition having a longitudinal slot therein for passage of air from the one chamber to the other, means for heating the air passing through said duct, a mesh-type humidifier in the air admission chamber of said duct, and means for supplying a regulated quantity of humidifying fluid to said humidifier, a duct extending longitudinally of the upper portion of the passenger space of the vehicle for supplying cool air thereto, air cooling means, 10 means for forcing air through said warm air duct, means for forcing air cooled by the cooling means or for supplying outside atmospheric air through the cool air duct, and temperature controlled means for automatically and alternately cutting in and cutting out the heating means and warm and cool air forcing means for maintaining a substantially uniform degree of temperature in the passenger space.
11. In an air conditioning apparatus for passenger vehicles, a warm air distributing conductor located at one side of the vehicle adjacent to the floor line thereof, said conductor having a heating compartment spaced at one side from the adjacent side wall of the vehicle, and in communication at its opposite side with the vehicle, means for heating the air passing through said duct, means for humidifying the air passing therethrough, a duct extending longitudinally of the upper portion of the passenger space of the vehicle for supplying cool air thereto, air cooling means, means for forcing air through said warm air duct, means for forcing air cooled by the cooling means or for supplying outside atmospheric air through the cool air duct, and temperature controlled means for automatically and alternately cutting in and cutting out the heating means and warm and cool air forcing means for maintaining a substantially uniform degree of temperature in the passenger space.
12. In an air conditioning apparatus for passenger vehicles, a warm air distributing conductor located at one side of the vehicle adjacent to the floor line thereof, said conductor having a heating compartment at its side facing the interior of the vehicle and provided with distributing outlets communicating therewith and having an air admission compartment communicating with said heating compartment and located between the same and the adjacent wall of the vehicle, means for heating the air passing through said duct, means for humidifying the air passing therethrough, a duct extending longitudinally of the upper portion of the passenger space of the vehicle for supplying cool air thereto, air cooling means, means for forcing air through said warm air duct, means for forcing air cooled by the cooling means or for supplying outside atmospheric air through the cool air duct, and temperature controlled means for automatically and alternately cutting in and cutting out the heating means and warm and cool air forcing means for maintaining a substantially uniform degree of temperature in the passenger space.
